TROPHY OR SIMILAR ARTICLE

John A. Santner, Skokie, Ill., assignor to Dodge,
Inc., Chicago, Ill., a corporation of Illinois

Application July 1, 1950, Serial No. 10,915

Term of patent 7 years

(Cl. D29—28)

To all whom it may concern:

Be it known that I, John A. Santner, a citizen of the United States, residing at Skokie, county of Cook, and State of Illinois, have invented a new, original, and ornamental Design for a Trophy or Similar Article, of which the following is a specification, reference being had to the accompanying drawing, forming a part thereof, in which—

Fig. 1 is a top plan view of the trophy or similar article, showing my new design;

Fig. 2 is a front elevational view thereof;

Fig. 3 is a side elevational view of my trophy or similar article.

The dominant features of my design reside in the portions shown in full lines.

I claim:

The ornamental design for a trophy or similar article, as shown and described.

JOHN A. SANTNER.
